Inventor:

Elmer E. Higman,

F. G. Fischer,
Attorney.

UNITED STATES PATENT OFFICE.

ELMER E. HIGMAN, OF KANSAS CITY, KANSAS.

SLAUGHTERING DEVICE.

Application filed March 24, 1924. Serial No. 701,386.

To all whom it may concern:

Be it known that I, ELMER E. HIGMAN, a citizen of the United States, residing at Kansas City, in the county of Wyandotte 5 and State of Kansas, have invented certain new and useful Improvements in Slaughtering Devices, of which the following is a specification.

My invention relates to improvements in 10 slaughtering devices and one object is to provide a knife whereby animals may be slaughtered in a swift, sanitary and humane manner.

A further object is to provide a slaughtering 15 device whereby the blood may be drawn from the arteries and veins of the animal and conducted directly to a sealed container without exposure to dust, bacteria of the air, or other contamination, thereby rendering the blood especially desirable for use in the preparation of serum.

Other objects will hereinafter appear, and in order that the invention may be fully understood, reference will now be had to the 25 accompanying drawing, in which:

Fig. 1 is an elevation of the slaughtering device.

Fig. 2 is a longitudinal section thereof on line II—II of Fig. 1.

Fig. 3 is a cross section on line III—III of Fig. 1.

Referring now in detail to the various parts, 2 designates a tubular body having an extension 4 projecting at an angle therefrom and provided with an outlet port 6. Said tubular body 2 is provided at its forward end with a removable extension 8 having inlet ports 10. The forward end 12 of the extension 8 is of conical formation and 40 has a slot 13 to receive the rear end of a blade 14 having tapered lugs 16, which are drawn against the corresponding portions of the extension 8 by a tapered screw 18, thereby firmly seating the blade 14 in said conical end 12.

The rear end of the tubular body 2 is provided with a removable hollow handle 20 through which a valve stem 22 axially extends. The rear end of said valve stem 22 is provided with a handle 24, while its forward end, which projects into the tubular body 2, is equipped with a valve 26 yieldably held against a shoulder 28 on the stem 22 by a coil spring 30, which is held in 55 position by a nut and washer 32 and 34,

respectively, on the forward end of said stem 22.

The valve 26 is provided at its front and rear margins with cutting edges 36, which fit snugly but slidably within the extension 8 and coact with an annular blade 38 in preventing the inlet ports 10 from becoming clogged as will hereinafter appear. The annular blade 38, which slidably embraces the extension 8, has front and rear cutting edges 40 and 42, respectively, and is connected to the valve 26 by suitable means such as screws 44 which extend through the inlet ports 10.

The valve 26 is normally held to its seat 46 to shut off communication between the inlet ports 10 and the outlet port 6 through the action of a coil spring 48 bearing at one end against a shoulder 50 in the rear portion of the handle 20 and at its opposite end against a disk 52, slidably arranged within the handle 20 and secured to the valve stem 22 by suitable means such as a pin 54.

56 designates a latch adapted to fit into a notch 58 in the valve stem 22 to hold the same in retracted position against the action of the spring 48 and to normally hold the valve 26 against its seat 46 in order to close communication between the ports 10 and 6. The latch 56 is controlled by a small lever 60 pivotally connected to the rear portion of the handle 20. A coil spring 62 is interposed between the handle 20 and the lever 60 to cause the same to yieldably hold the latch 56 in the notch 58. The valve stem 22 is also provided with a notch 64 at the rear of the notch 58, so that said valve stem 22 and the valve 26 may be locked in their forward position.

The rear end of the tubular body 2 is provided with a stuffing-box 66 to form a tight joint around the valve stem 22. A leather or other suitable washer 68 is seated in the valve 26 around the stem 22, to receive the thrust of the spring 30 and prevent blood from the slaughtered animal entering the axial opening in the valve 26 where it would congeal and prevent the spring 30 from cushioning said valve 26 when the same is drawn against its seat 46.

The extension 4 of the tubular body 2 is equipped with a hose 70, which may be connected to a sealed container, not shown.

72 designates a curved retaining device 110

which is connected at its rear end by a pivot 74 to the valve 26 and has its forward end extending through a hole 76 in the forward portion of the extension 8.

- 5 In practice a hog or other animal may be slaughtered and its blood conducted to the container as follows: With the parts in the position shown by Fig. 2, the blade 14 is plunged into the throat of the animal to sever the jugular vein, the device being inserted in the wound up to the extension 4. After the blade 14 has been thrust home the same hand which grasps the handle 22 actuates the lever 60 to disengage the latch 15 56 from the valve stem 22, which is immediately forced forward by the spring 48 and carries the valve 26 therewith to establish communication between the inlet ports 10 and the outlet port 6. The blood may now 20 flow freely from the wound into the container to which the hose 70 is connected, which container is preferably under a vacuum that quickly draws the blood from the animal. The wound is held open by the 25 tubular extension 8, so that the blood may flow freely until all has been drained into the container.

When the valve 26 is forced forwardly by the action of the spring 48, as above stated, 30 it forces the retainer 72 outwardly through the hole 76 and into the wound at substantially right angles to the blade 14, for the purpose of reliably holding the same in the wound. This leaves the operator free to 35 plunge other of the devices into other animals as they are carried past by suitable means, such as an overhead rail, to another operator who removes the devices from the slaughtered animals after the blood has been 40 drained therefrom.

During the act of withdrawing the devices from the slaughtered animals the handles 24 are first pulled backwardly to withdraw the respective retainers 72 from the wounds, after 45 which the device can be easily removed by pulling back on the handle 20, after the latch 56 has been withdrawn from the notch 64.

From the foregoing description it is apparent that I have provided a slaughtering device embodying the advantages above pointed out; and while I have shown and described the preferred construction, combination and arrangement of parts, I reserve 55 the right to make such changes as properly fall within the spirit and scope of the invention as claimed.

Having thus described my invention, what I claim and desire to secure by Letters Patent, is:

- 60 1. A slaughtering device consisting of a tubular body having inlet and outlet ports, a valve operably mounted in said body to open and close communication between said ports, cutting means movable across the inlet

port and controlled by the valve, means for controlling said valve, and a blade at the forward end of said body.

2. A slaughtering device consisting of a tubular body having inlet and outlet ports, 70 a valve operably mounted in said body to open and close communication between said ports, means for controlling said valve, a blade at the forward end of said body, and a curved retaining device extending through 75 the tubular body and operably connected to the valve to be forced outwardly thereby as said valve moves forwardly to open communication between the inlet and outlet ports.

3. A slaughtering device consisting of a tubular body having inlet and outlet ports, 80 a valve operably mounted in said body to open and close communication between said ports and provided with an annular knife 85 edge fitting snugly within the body to keep the inlet ports clear, means for controlling said valve, a blade at the forward end of said body, and a handle at the rear end of said body.

4. A slaughtering device consisting of a tubular body having inlet and outlet ports, a valve operably mounted in said body to open and close communication between said ports, means for controlling said valve, a blade at 90 the forward end of said body, and an annular knife movable with the valve to keep the inlet ports clear, substantially as described.

5. A slaughtering device consisting of a tubular body having inlet and outlet ports, 100 a valve operably mounted in said body to open and close communication between said ports, a stem connected to said valve to control the same, means for normally holding said stem in retracted position and thereby holding the valve seated, spring means for advancing said stem when released from said holding means and a blade at the forward end of said body.

6. A slaughtering device consisting of a 110 tubular body having inlet and outlet ports, a valve operably mounted in said body to open and close communication between said ports, a stem connected to said valve to control the same, a handle connected to the rear of the tubular body and through which said stem extends, latch means mounted in said handle for holding said stem in retracted position and thereby holding the valve to its seat and a knife at the forward end of 115 said body.

7. A slaughtering device consisting of a tubular body having inlet and outlet ports, a valve operably mounted in said body to open and close communication between said 120 ports, a stem connected to said valve to control the same, a handle connected to the rear of the tubular body and through which said stem extends, latch means mounted in said handle for holding said stem in retracted 125 position and thereby holding the valve to its seat and a knife at the forward end of said body.

position and thereby holding the valve to its seat, a disk within said handle and fixed to the stem, and a coil spring within the handle and interposed between the rear end thereof and said disk to effect the opening of the valve when the latch is disengaged from said stem, and a knife at the forward end of said body.

8. A slaughtering device consisting of a tubular body having inlet and outlet ports, a valve reciprocably mounted in said body to open and close communication between

said ports, a stem yieldably connected to said valve to control the same, latch means for securing said stem in advanced and retracted positions, and a blade at the forward end of said body. 15

9. In a slaughtering device, a tubular body having inlet and outlet ports, means movable across the inlet port to keep the same clear, and a knife secured to the forward end of said body. 20

In testimony whereof I affix my signature.

ELMER E. HIGMAN.
